UNITED STATES PATENT OFFICE.

ELLA C. FINDLEY, OF VICTORIA, BRITISH COLUMBIA, CANADA.

SWITCH.

1,420,984.

Specification of Letters Patent. Patented June 27, 1922.

Application filed December 15, 1920. Serial No. 430,871.

To all whom it may concern:

Be it known that I, ELLA C. FINDLEY, a citizen of the United States, residing at Victoria, in the Province of British Columbia 5 and Dominion of Canada, have invented certain new and useful Improvements in a Switch, of which the following is a specification.

This invention relates to a switch and has 10 for its object to provide a compound switch whereby a switch-board operator is enabled to connect all the rooms in a hotel, rooming house, boarding house, or an apartment house with one operation. Thus a signal may be 15 given simultaneously to the occupants of the various rooms that there is a fire or some other impending danger.

A further object of the invention is to 20 generally improve upon switches of this character by providing a device which will be extremely simple, durable and inexpensive construction, one which is efficient and reliable in operation, and well adapted to the purpose for which it is designed.

25 With these and numerous other objects in view, the invention resides in certain novel features of construction, and the combination and arrangement of parts as will be hereinafter more fully described and claimed.

30 In the drawing:-

Figure 1 is a plan view of the switch,

35 Figure 2 is a section taken on the line 2—2 of Figure 1 looking in the direction of the arrow,

Figure 3 is a section taken on the line 3—3 of Figure 1 looking in the direction of the arrow, and

40 Figure 4 is a section taken on the line 4—4 of Figure 1.

45 Referring to the drawing in detail it will be seen that 1 designates a stud to which is swivelly mounted a switch. The switch consists of the body 2 having a plurality of arms 3 radiating therefrom. A plurality of contact clips 4 are mounted on the arms 3 and these clips 4 are provided with a right angled extension 5 having an aperture therein so that a screw 6 may be passed therethrough for permanently attaching the con-

tact clips to the arms 3. A plurality of contact points or terminals are suitably situated on a wall and are arranged in series and each series will radiate from the center of the switch as is shown in the drawing. Thus upon rotation of the switch one arm will pass over each series so that the clips 4 will engage the contact points 7 and close suitable circuits to various rooms for the purpose of ringing the usual telephone bell or a like signal. One of the arms 3 is preferably made longer than the remaining arms and is provided at its terminal with a knife switch 8 which is adapted to engage the switch clip 9 so that a circuit may be closed to a gong or some other audible signal placed in the building. This knife switch formed by the members 8 and 9 is an auxiliary switch.

An eye 10 is preferably placed upon the terminal of the last mentioned arm 3 and a 70 rod 11 is loosely attached thereto. A support 12 having an eye 13 thereon is provided for receiving the rod 11 and a washer 14 is mounted upon the end of the rod 11 so that a coil spring 15 may be disposed between the 75 washer 14 and the eye 13 thus the spring will be compressed when the switch is rotated in a counter-clockwise direction and will normally have a tendency to place the switch in a closed position. A suitable stop 80 plug 16 is mounted in an aperture or opening in the wall and will engage one of the arms 3 so as to hold the switch in an open position as shown in Figure 1. A permanent stop 18 is situated a short distance 85 therefrom and will prevent the switch from rotating too far. Thus it will be seen that if the plug 16 is removed the spring 15 will force the switch to a closed position.

From the foregoing description, taken in 90 connection with the accompanying drawings, the construction and operation of the switch will be readily understood without a more extended explanation. As numerous changes in form, proportion and in the 95 minor details of construction may be resorted to without departing from the spirit of the invention, I do not wish to be limited

to the construction herein shown and described other than as claimed.

Having thus described my invention what I claim as new is:

- 5 A rotary switch comprising a body, arms radiating therefrom contacts on the arms, stationary contacts, stop means for holding the switch in an open position, a rod loosely mounted on one of the arms, a coil spring on

the rod for closing the switch upon removal 10 of the stop means.

In testimony whereof I affix my signature in presence of two witnesses.

ELLA C. FINDLEY.
